UNITED STATES PATENT OFFICE.

JOHN G. ELLENDT, OF ROCHESTER, NEW YORK.

APPARATUS FOR CLEANING BAGS.

1,156,280.

Specification of Letters Patent. Patented Oct. 12, 1915.

Application filed January 16, 1913. Serial No. 742,494.

To all whom it may concern:

Be it known that I, JOHN G. ELLENDT, a citizen of the United States, residing at Rochester, in the county of Monroe and State of New York, have invented certain new and useful Improvements in Apparatus for Cleaning Bags, of which the following is a specification, reference being had therein to the accompanying drawing.

10 My invention relates to improvements in apparatus for cleaning bags and similar receptacles, and is illustrated in one of its preferred forms in the accompanying drawings in which—

15 Figure 1 illustrates in vertical cross section, partly broken away, one type of apparatus showing an application of the invention. Fig. 2 is a cross section on the line 2—2 of Fig. 1 with parts broken away, and 20 Fig. 3 is a plan view illustrating a series of single units such as shown in Figs. 1 and 2 connected in such a manner as to operate together.

4 is the outer casing or box mounted upon 25 the base 5 provided with a removable front or door such as 6.

7 is a suitable standard secured upon the top of the base 5, said base being open at the top as indicated at 8—8'. At the base and 30 upon said standard are secured suitable bearings such as 9—10—11, the bearings 9 being permanently secured and the bearings 10—11 being free to slide upon the standard 7. Upon said bearings are preferably 35 pivotally secured connecting rods such as 12, 13 and 14, at the opposite ends of which are secured suitable slats or frames such as 15—16.

17 is a rod or other suitable connecting 40 means preferably secured to the bearing 10 and extending outside of the casing 4 mounted to slide within the bearings 18—19, the bearing 19 being provided with a suitable arm such as 20 serving as a support for the 45 hand lever 21 pivoted to the top of the sliding bar connection 17 as shown.

22 is a bag such as usually contains cement or other powdery substance which clings to the fibers thereof making it difficult to separate the same without inhaling the powder. 50 The top of the casing preferably terminates in a hopper such as 23 provided with a cover such as 24, and the lower end of the outer casing preferably communicates with

an exhaust flue such as 25 provided with a 55 damper or other suitable controlling means such as 26.

In operation a bag such as 22 is placed upon the frame 15—16 in the position shown in Fig. 1, after which the cover 24 is closed 60 and the damper 26 opened. By operating the handle 21 rapidly up and down it will be observed that the slide bar 17 connected to the bearing 10 causes the same to reciprocate vertically upon the standard 7 and 65 said bearing 10 being connected to the bearing 11 by the connecting rods 27—27', it will be understood that the frames or slats 15—16 are rapidly extended and withdrawn somewhat similar to the action of an umbrella frame when the same is rapidly 70 opened and closed. In this manner the powdered material clinging to the bag is beaten or shaken therefrom and drops to the bottom of the casing 4, passing through the 75 openings 8—8' thereof and accumulating within the chamber 28 as indicated by the reference character 29 thus making the same accessible through the opening or door 6. The flue 25 may be connected with any suitable 80 suction means or draft to assist in the release of the material from the bag and to carry off the same instead of allowing it to accumulate within the chamber 28.

Of course it will be understood that a 85 series of shakers or cleaners such as shown in Figs. 1 and 2 may be mounted in a single divided casing such as that indicated by the reference character 4^a in Fig. 3. In that case a single hand lever such as 30 may be 90 employed for operating a series of shakers or any other suitable power equipment may be supplied for that purpose. Of course it will be understood that various modifications may be made without departing from 95 the spirit of the invention as claimed.

I claim:

1. In an apparatus of the class described, an outer casing, an upright standard therein, a slide on said standard, upright slats on opposite sides of said standard, links pivoted to said slats and said slide, means to reciprocate said slide on said standard, and means to limit the endwise movement of said slats, whereby said slats are vibrated 100 radially of said standard.

2. In an apparatus of the class described, an outer casing, an upright standard there-

in, a slide on said standard, upright slats on opposite sides of said standard, links pivoted to said slats and said slide, means to reciprocate said slide on said standard, and 5 means to limit the endwise movement of said slats, whereby said slats are vibrated radially of said standard, said reciprocating means comprising a connecting bar secured

to said slide, and means outside the casing for operating said bar.

10

In testimony whereof I hereunto affix my signature in the presence of two witnesses.

JOHN G. ELLENDT.
